UNITED STATES PATENT OFFICE.

HENRY D. MARTIN, OF GRIFFIN, GEORGIA, ASSIGNOR TO DRAPER CORPORATION, OF HOPEDALE, MASSACHUSETTS, A CORPORATION OF MAINE

AUTOMATICALLY-THREADING SHUTTLE.

Application filed July 8, 1925. Serial No. 42,122.

To all whom it may concern:

Be it known that I, HENRY D. MARTIN, a citizen of the United States, and a resident of Griffin, in the county of Spalding and 5 State of Georgia, have invented an Improvement in Automatically-Threading Shuttles, of which the following description, in connection with the accompanying drawings, is a specification, like characters on the 10 drawings representing like parts.

This invention relates to shuttles and more particularly to self-threading shuttles provided with a friction tension means for imparting tension to the thread during 15 weaving.

Shuttles have heretofore been provided with various types of tension means for exerting the desired tension on the thread during weaving, but in shuttles of the automatically threading type it has been found that the character and location of the thread 20 tension means must be such as not to interfere with the automatically threading portion of the shuttle on the pick thereof following replenishment. Any tension means that would prevent the free swirling action of the thread on its first pick following replenishment is liable to cause a failure of 25 shuttle threading and may result in breakage of the thread when the shuttle is picked.

It is often desirable to vary the tension of the thread, and this is especially observable when different kinds or characters of filling 30 are employed. One of the objects of the present invention, therefore, is to provide a friction tension, preferably in the form of a pad of textile material or felt, or like substance, which may be so positioned relative 35 to the automatically threading features of the shuttle as not to interfere therewith, and yet provide proper tension on the thread after the shuttle has been properly threaded. A still further object of the invention is to 40 provide a friction pad or tension device of the general character described, which may be readily adjusted to vary the tension on the thread in accordance with the character 45 of the thread in use.

The above and other novel features of the invention will best be made clear from the following description and the accompanying drawings of one good form thereof.

In the drawings:

Fig. 1 is a plan view of an automatically

threading shuttle provided with the present invention;

Fig. 2 is a detailed perspective view on an enlarged scale showing a threading block provided with the tension device of the present invention;

Fig. 3 is a side elevation of the threading block on an enlarged scale, showing a modified form of the invention;

Fig. 4 is a detached detail showing the 65 split ferrule which may be employed for holding the tension pad in different positions for varying the tension on the yarn; and

Fig. 5 is a still further modification showing another means for holding the pad in 70 adjusted position for varying the tension.

In automatically threading shuttles wherein preliminary threading is effected on the first pick of the shuttle after replenishment, 75 the thread is withdrawn from the filling carrier or bobbin in the shuttle as the shuttle is picked on the first flight of the shuttle following replenishment, and one of the purposes of the present invention is to utilize 80 the swirling action of the thread to effect preliminary threading, and yet provide in connection with such automatically threading shuttle a tension pad which will not interfere with the preliminary threading and 85 will at the same time present the desired frictional tension on the thread during subsequent weaving after the shuttle has been fully threaded.

In the drawings, the shuttle 1 is provided 90 with the usual bobbin chamber 2 in which the filling carrier 3 is detachably supported in a manner now well understood in the art. Frontward of the bobbin chamber the shuttle is provided with a threading 95 block receiving chamber 4 in which the threading block 5 is secured, preferably by means of an opening or hole 6 extending transversely through the threading block and engaged by the usual cross bolt. The 100 threading block has the longitudinally extending thread passage 7 open at its top and laterally thereof is the side delivery eye of the shuttle, as at 8.

The threading block as herein shown is of 105 the general type shown and described more fully in the patent to Edward S. Stimpson, No. 1,538,224, dated May 19, 1925. That is, it is preferably formed of cast iron, having a smooth, rust-resisting surface which offers 110

no impediment to the free passage of the thread. While the present invention is especially advantageous in use with the threading block shown and described in the 5 Stimpson patent mentioned, it might also be employed in connection with other forms of threading blocks for automatically threading shuttles.

In the present instance the threading 10 block in addition to the open threading slot 7, has a thread director 9, the end portion of which extends transversely of but does not entirely cross the thread passage, and is also provided with a thread guide or bridge 15 15 at the forward end of the longitudinally extending thread passage over which the thread *a* passes on its way to the side delivery eye.

In accordance with the present invention, 20 a friction pad extends transversely of the longitudinally extending thread passage at the front portion thereof below the bridge, as shown, so that during preliminary threading, the swirling action of the thread finds 25 no obstruction by contact with the tension pad.

The tension pad 12 is arranged transversely of the longitudinally extending thread passage and, as indicated in Fig. 2, 30 the threading block may be provided with a transversely extending opening or recess 13 below the bridge, in which the body portion of the friction pad 12 may be held.

When the tension pad of the present invention is employed in connection with a threading block having a bridge over which the thread passes on its way to the side delivery eye, the pad is preferably located frontward or forward of the bridge, being 40 secured in place below the bridge to engage the thread on its way to the side delivery eye, so that tension is applied to the thread between the longitudinally extending thread passage and the side delivery eye.

Where the tension pad is formed and held as indicated in Fig. 2, the body portion 14 of the pad will be compressed and pushed transversely into the opening 13 in the threading block, while the tension portion 50 of the pad forward of the bridge extends transversely of the thread passage and is located in front of and below the bridge, as indicated in Figs. 1 and 2.

When the character of filling is changed 55 in the shuttle or a different tension is desired, the pad, as indicated in Fig. 2, may be turned in the transverse opening 13 about its transversely extending axis, with the result that the tensioning portion of the pad 60 will be raised nearer to the top surface of the bridge and therefore act more energetically upon the thread on its way from the thread passage to the side delivery eye.

In Fig. 3, the threading block 5, which is 65 shown of substantially the same character

as that of Figs. 1 and 2, has the transverse opening 13 occupied by the split ferrule 15 in which the pad or friction material 12 is held. The ferrule 15 extends transversely of the thread passage and is preferably coincident in length with the transverse length of the tension pad and may be held in the opening 13 of the threading block by frictional engagement of the walls of the split ferrule 15 with the walls of the opening. 70 The ferrule 15, as indicated in Figs. 3 and 4, is provided at one edge with notches or recesses 16 by which the ferrule may be conveniently turned to vary the position of the pad about its axis extending transversely of the thread passage to thereby vary the tension that may be applied to the thread between the longitudinally extending thread passage and side delivery eye. 75

The ferrule 15, as hereinbefore stated, 80 has the split portion 17 and may be conveniently formed of spring metal, so that when the pad 12 is placed within the ferrule, the projecting portion of the pad, as indicated in Fig. 3, may be raised or lowered, 85 and consequently vary the tension of the thread by turning the ferrule about its axis extending transversely of the thread passage.

In Fig. 5 the threading block may be of 90 the same general type as those already described or of any other type, and instead of making the transverse opening 13 in the threading block below the thread passage, the threading block may be provided with a recess 18, in which the pad of flexible material, such as felt, may be secured by the block 19 having the complementary recess 20, and held to the block by a screw or other fastening means, as 21. As indicated in 95 Fig. 5, the block 9 has a bearing shoulder 100 portion 22 which bears against an abutment on the threading block, so that upon setting up the screw 21, the pad of frictional material may be securely held in place and in 105 any desired position of adjustment for varying the tension exerted upon the thread between the longitudinally extending thread passage and the side delivery eye. 110

The pad itself, as indicated in Fig. 5, is 115 formed of two layers of friction material 23 and 24 which may be either pieces of felt or woven fabric, one upon the other, as indicated in Fig. 5. The pad shown and described with respect to the remaining figures of the drawings may be similarly formed 120 of textile material, either woven or felted, or indeed, any suitable friction pad construction.

From the construction described it will be 125 apparent that the friction pad, by reason of its position relative to the automatically threading block, offers no obstruction to the swirling action of the thread during preliminary threading following replenishment 130 of filling, and asserts itself mainly when the

shuttle has become fully threaded and the thread passes from the longitudinally extending thread passage to the side delivery eye. So, also, when different kinds of filling are employed, and it is desired consequently to vary the tension of the thread, the pad may be adjusted about its axis extending transversely of the thread passage to present more or less of the pad to actively tension the thread on its way to the side delivery eye.

What is claimed is:

1. In an automatically threading loom shuttle, the combination of a threading block having a longitudinally extending thread passage, a bridge over which the thread passes to the side delivery eye, and a thread tension pad extending transversely of a thread passage frontward of and a substantial distance below the bridge to engage and tension the thread as it is deflected downwardly from the bridge towards the side delivery eye.
2. In an automatically threading loom shuttle, the combination of a threading block having a longitudinally extending thread passage, a bridge over which the thread passes to the side delivery eye, a thread tension pad extending transversely of the thread passage frontward of the bridge to engage and tension the thread between the thread passage and side delivery eye, and means permitting the tension pad to be moved to present more or less tension surface to the thread.
3. In an automatically threading loom shuttle, the combination of a threading block having a longitudinally extending thread passage with a bridge at the forward end thereof and provided with a transversely extending pad holding recess below the bridge, and a tension pad which is held in

said recess by the engagement of the pad therewith to tension the thread below the bridge between the longitudinally extending thread passage and side delivery eye. 45

4. In an automatically threading loom shuttle, the combination of a threading block having a longitudinally extending thread passage, a tension pad extending 50 transversely of the thread passage at the forward end thereof over which the thread is drawn towards the side delivery eye, and means for holding the tension pad in different positions of adjustment to vary the amount of frictional pad surface presented to the thread on its way to the side delivery eye.

5. An automatically threading loom shuttle having a longitudinally extending thread 60 passage and side delivery eye, a tension pad extending transversely of the thread passage at the forward end thereof for tensioning the thread between the thread passage and side delivery eye, and means for holding the tension pad in different positions of rotative adjustment about its transversely extending axis to vary the tension on the thread. 65

6. An automatically threading loom shuttle having a longitudinally extending thread passage and side delivery eye, a tension pad extending transversely of the thread passage at the forward end thereof for tensioning the thread between the thread passage and 70 side delivery eye, and a split ferrule for holding the pad in different positions of rotative adjustment about its transversely extending axis to vary the tension on the thread. 75

In testimony whereof, I have signed my name to this specification.

HENRY D. MARTIN.
